ANTICREEPING CLAMP FOR RAILS.

1,127,314.

Specification of Letters Patent.

Patented Feb. 2, 1915.

Application filed September 8, 1914. Serial No. 860,735.

To all whom it may concern:

Be it known that I, MELCHIOR SWARNY, a subject of the King of Hungary, residing at Homestead, in the county of Allegheny and 5 State of Pennsylvania, have invented certain new and useful Improvements in Anti-creeping Clamps for Rails, of which the following is a specification, reference being had therein to the accompanying drawing.

10 This invention relates to anticreeping clamp for rails and has for its object to provide a device of such character, in a manner as hereinafter set forth, to prevent longitudinal movement, known as creeping, 15 which is caused by heavy travel over the track and is of general occurrence when some means is not provided to arrest such longitudinal movement.

20 A further object of the invention is to provide a device of such class, in a manner as hereinafter set forth, which is simple in its construction and arrangement, strong, durable, efficient and convenient in its use, readily set up and comparatively inexpensive to manufacture.

25 With the foregoing and other objects in view the invention consists of a novel construction, combination and arrangement of parts as hereinafter more specifically described and illustrated in the accompanying drawings wherein is shown an embodiment of the invention, but it is to be understood 30 that changes, variations and modifications can be resorted to which come within the scope of the claims hereunto appended.

35 In the drawings wherein like reference characters denote corresponding parts throughout the several views:—

Figure 1 is a perspective, partly in section 40 and partly broken away, of a track rail showing the adaptation of an anti-creeping clamp in accordance with this invention. Fig. 2 is a perspective view of one of the clamp members. Fig. 3 is a perspective view 45 of the clamping head. Fig. 4 is a perspective view, broken away, of one of the clamping bars. Fig. 5 is a perspective view of a locking wedge.

Referring to the drawings in detail 1 de-

notes a base, 2 the web and 3 the head of a 50 track rail and positioned against each side of the web 2, as well as overlapping the base 3, is a clamping bar 4, cut away intermediate its ends, to provide a pocket 5.

The reference character 6 denotes a bar 55 which is adapted to be positioned below the base 1, and has one end enlarged as at 7, to provide a shoulder 8 which when the bar 6 is in position abuts against one longitudinal edge of the base 1. The enlarged end 7 60 is provided with a vertically disposed wedge-shaped opening 9. The other end of the bar 6 terminates in a clamping head 10 which is adapted to overlap one side of the base 1 and seat in the pocket 5. The bar 6 in connection with the head 7 provides what is termed a clamping member.

Associated with the enlarged end 7 of the bar 6 is a clamping head comprising a base 11 and an extension 12 which is adapted to 70 overlap the base 1 and seat in the pocket 5 of a clamping bar. The base 1 is formed with an opening 13 for the reception of the enlarged end 7 of the bar 6 and said clamping head is further provided with a vertically 75 disposed opening 14, which registers with the opening 9.

Extending down through the openings 14, 9 is a clamping wedge 15, having a transverse opening 16 for the passage of a hold 80 fast device, not shown. When the wedge 15 is in the position shown in Fig. 1, the clamping head which is mounted upon the end 7 of the bar 6 is fixedly secured in position. The clamping head when seated in the pocket 85 5 securely clamps the bar 4 against the web 2.

What I claim is:—

A device for the purpose set forth comprising a pair of clamping bars adapted to 90 be positioned at opposite sides of a track rail and overlap the base thereof, each of said bars having its outer face provided intermediate its ends with a pocket, a clamping member including a bar having one end 95 enlarged and provided with a vertical opening and its other end formed with a clamping head adapted to overlap one side of a

base of a rail and seated in one of said pockets, a clamping head mounted upon said enlarged end and capable of overlapping the other side of a base of a rail and seated in a 5 pocket of the other clamping bar, and means for connecting the last mentioned clamping head to said clamping member.

Copies of this patent may be obtained for five cents each, by addressing the "Commissioner of Patents, Washington, D. C."

In testimony whereof I affix my signature in the presence of two witnesses.

MELCHIOR SWARNY.
